UNITED STATES PATENT OFFICE.

EDWIN N. DAVIS, OF LODI, WISCONSIN.

CRATE.

No. 883,002.

Specification of Letters Patent. Patented March 24, 1908.

Application filed March 8, 1907. Serial No. 361,301.

To all whom it may concern:

Be it known that I, EDWIN N. DAVIS, a citizen of the United States, residing at Lodi, in the county of Columbia and State of Wisconsin, have invented certain new and useful Improvements in Crates; and I do hereby declare the following to be a full, clear, and exact description of the invention, such as will enable others skilled in the art to which it appertains to make and use the same.

My invention relates to new and useful improvements in crates and more particularly to that class adapted to be used for crating eggs or like perishable commodities and my object is to provide a crate that may be readily knocked down and folded compactly together for reshipping.

A further object is to provide means for quickly and positively securing the parts of the crate together.

A still further object is to provide reinforcements for the side walls of the crate.

Other objects and advantages will be hereinafter referred to and more particularly pointed out in the claims.

In the accompanying drawings which are made a part of this application, Figure 1 is a perspective view of my crate complete, showing the same in its assembled position. Fig. 2 is a top plan view thereof with the cover removed. Fig. 3 is a longitudinal sectional view thereof as seen on line 3—3 Fig. 4. Fig. 4 is a sectional view as seen on line 35 4—4 Fig. 3. Fig. 5 is an end elevation of the crate folded and ready for reshipment, and, Fig. 6 is a perspective view of a lining adapted to be placed in the upper and lower portion of the crate.

Referring to the drawings in which similar reference numerals designate corresponding parts throughout the several views, 1 indicates the floor or base of my improved crate to the longitudinal edges of which are secured rails 2 while blocks 3 are disposed across the ends of the section and between the rails, said blocks extending slightly above the rails, said rails and blocks forming a cavity into which are disposed side and end walls 4 and 5, respectively, said walls extending upwardly from the floor and forming a suitable receptacle for various articles when assembled together.

The floor 1, rails 2 and blocks 3 are preferably constructed of wood while the side and end walls are preferably constructed of sheet

metal thereby lending rigidity to the parts of the device, at the same time decreasing the weight and cost thereof. The longitudinal edges 6 of the end walls 5 are directed at right angles to the face of the end walls and are provided with L-shaped terminals 7 with which are adapted to interlock similar terminals 8 at the ends of the side walls 4 so that when said terminals are interlocked with each other the end and side walls will be held rigidly in a vertical position.

In order to divide the space between the side and end walls into compartments and at the same time reinforce the side walls, I provide a partition wall 9 which is supported between ears 10 at the central portion of the side walls, said ears being preferably formed by striking in portions of the side walls and separating the struck in portions at their center and then forming the separated portions at right angles to the inner faces of the side walls, said ears being arranged in pairs and spaced a sufficient distance apart to receive the partition wall.

Disposed over the side and end walls is a cover 11, said cover having rails 12 similar to the rails on the floor section and parallel therewith while the ends of the cover are provided with blocks 13 which are secured between the rails 12 and are less in depth than said rails.

Secured to the end walls 5 at a point adjacent the upper ends thereof, are strips 14, upon which the blocks 13 are adapted to rest when the crate is in its assembled position and in order to secure the cover in position over the walls, I extend upwardly from the strips 14, eye-bolts 15 with which is adapted to engage the angular end 16 of a spring latch 17, said latch having one of its ends fixed to the block 13 and in order to readily detach the angular end 16 from the eye-bolt 15, I provide a tapered socket 18 in the blocks 13 immediately in the rear and extending above the spring latch 17 so that an object may be readily inserted back of the spring latch and outward pressure directed thereon which will result in disengaging the angular end 16 from the eye-bolt.

In assembling the several parts of my improved crate together, the end walls 5 are first disposed in position and in order to positively hold the same into engagement with the blocks 3, I secure to each of said blocks, a pair of upwardly extending lugs 19 which are adapted to extend through slots 20 in the

in the end walls after which the side walls 4 are elevated to the upper ends of the end walls and the terminals 7 and 8 interlocked with each other by moving the side walls 4 downwardly which will result in holding the side and end walls rigidly together and the cover 11 is then disposed over the upper end of the walls until the blocks 13 rest upon the strips 14 when the spring latches 17 will engage the eye-bolts 15 and the cover thus held securely in position over the walls.

When the crate has reached its destination and the contents thereof have been removed the end and side walls are separated and the several sections thereof placed on the floor 1 after which the cover 11 is disposed over the folded parts, the rails 12 resting upon the rails 2 and the blocks 13 resting upon the blocks 3, the blocks 3 being provided with eye-bolts 21 with which the spring latches 17 engage thereby securing the several parts in their folded position. By forming the blocks 3 of a greater height than the rails 2 and the blocks 13 of less depth than the rails 12 it will be seen that a portion of the block 3 will extend between the rails 12 and prevent the eye-bolts from becoming broken from a blow delivered to the bottom section or cover.

30 When the side walls 4 are formed of sheet metal the same are preferably reinforced by providing ribs 22 which extend longitudinally of the side walls and are formed by bending out portions of the material forming the side walls.

In Fig. 6 of the drawings I have shown a preferred form of lining 23 which is adapted to be placed over the under surface of the cover and the upper surface of the floor section, when the crate is employed for shipping crackers or like articles, the object being to render the crate moist proof. The lining used to cover the floor section is provided at one end with notches 24 so that the same may be placed into or removed from the cavity formed by the side rails and end blocks while each edge of the lining is provided with a flange 25 which is directed at right angles to the plane of the lining and bent upon itself to form hooks 26 and as shown by dotted lines in Fig. 4 of the drawing when the lining is placed within the crate any dirt or foreign particles entering the crate between the side walls 4 and the rails 2 will be prevented from entering the interior of the crate.

It will now be seen that I have provided a very cheap and economical crate and one that will be perfectly rigid when assembled together and not readily destroyed or injured in shipping and it will further be seen that I have provided a crate that can be quickly knocked down or set up and when knocked

down will occupy a minimum amount of space and further that I have provided means for readily securing the several parts 65 of the crate together.

What I claim is:

1. The herein described crate comprising a floor, rails at the edges of said floor, blocks interposed between said rails and at the ends 70 of said floor, said blocks and rails being of different height upwardly extending hooks on said blocks, end walls having slots therein adapted to receive said hooks, L-shaped terminals on said end walls, side walls having 75 L-shaped terminals at the ends thereof adapted to telescopically interlock with the terminals on the end walls, said side walls having ribs, a partition wall adapted to engage inwardly directed ears on the side walls, 80 a cover for said walls said cover having rails at its edges and blocks at the ends thereof between said rails, said rails and blocks being opposite in height with respect to those on the floor thereof, and a spring-latch on the 85 upper blocks adapted to engage eye-bolts on the strips and lower blocks whereby said cover may be secured over the walls in their folded or assembled position.

2. A crate of the class described comprising a floor section, rails secured to the edges of said floor section, blocks between the ends of said rails and extending above the same, said rails and blocks forming a cavity, end walls adapted to enter said cavity and engage 95 said blocks, hooks on the blocks adapted to engage and hold the end walls from upward movement, L-shaped terminals on the end walls, side walls adapted to enter said cavity and engage said rails, L-shaped 100 terminals on said side-walls adapted to telescopically receive the terminals on the end wall, ears arranged in pairs and formed by directing inwardly portions of the side walls, a partition wall adapted to engage said ears 105 and longitudinal ribs on said side walls.

3. The herein described crate comprising a floor, end and side walls for said floor, means to hold said walls into engagement with the floor, a cover for said walls, a lining 110 for said cover and floor, said lining having right angled extensions thereon and hooked terminals at the free edges of said extensions whereby when said linings are placed in position foreign particles will be excluded from 115 the interior of the crate.

In testimony whereof I have signed my name to this specification in the presence of two subscribing witnesses.

EDWIN N. DAVIS.
